UNITED STATES PATENT OFFICE.

LUTHIER V. MOULTON, OF GRAND RAPIDS, MICHIGAN.

DESIGN FOR A WHEEL-HOUSE FOR MARINE VELOCIPEDES.

SPECIFICATION forming part of Design No. 27,154, dated June 1, 1897.

Application filed May 3, 1897. Serial No. 634,954. Term of patent 14 years.

To all whom it may concern:

Be it known that I, LUTHER V. MOULTON, a citizen of the United States, residing at Grand Rapids, in the county of Kent and State of Michigan, have invented and produced a certain new and original Design for a Wheel-House for Marine Velocipedes; and I do hereby declare the following to be a full, clear, and exact description of the invention, reference being had to the accompanying drawings, forming part thereof.

This design relates to the wheel-house of marine velocipedes and analogous structures, and the distinctive features thereof are the oppositely-curved sills, the segmental curved bars, and the radial bars connecting the same, as more fully illustrated in the accompanying drawings, in which—

Figure 1 is a perspective of a wheel-house embodying said design, and Fig. 2 a side elevation of the same.

Like letters refer to like parts in both of the figures.

A represents the sill of the wheel-house, having a general inclination of about forty-

five degrees, being nearly horizontal at its extreme ends and oppositely curved longitudinally, the lower part being convex on the under side and concave on the upper side and the upper part having an opposite 30° curvature.

B is a bar having a substantially semicircular longitudinal curvature and joined at each end to the respective ends of the sill A.

D is a semicircular plate near the middle 35 of the sill A, and C C C are radial bars extending from said plate to the bar B and dividing the space between the bars A and B into four substantially equal parts.

Having thus fully described my invention, 40 what I claim is—

The design for a wheel-house for marine velocipedes, substantially as shown and described.

In testimony whereof I affix my signature 45 in presence of two witnesses.

LUTHIER V. MOULTON.
